UNITED STATES PATENT OFFICE.

JOHN DOMINICZAK, OF BRADDOCK, PENNSYLVANIA.

ELECTRICAL SWITCH.

Application filed April 29, 1926. Serial No. 105,469.

This invention relates to electric switches and has special reference to switches of the type called pole changers being in the form of a double pole double throw switch.

5 One object of the invention is to provide an improved general construction of switches of this character wherein by the provision of a continuous contact with the source of current supply, one lead and terminal can be eliminated.

10 A second object of the invention is to provide an improved switch of this type wherein the switch is adapted to be sunk in a wall or floor and operated by a pair of push buttons.

15 A third important object of the invention is to provide a novel and improved switch especially adapted to control a light or system of lights from a number of different points.

20 With the above and other objects in view as will be hereinafter apparent, the invention consists in general of certain novel details, of construction and combinations of parts 25 hereinafter fully described, illustrated in the accompanying drawings and specifically claimed.

25 In the accompanying drawings like characters of reference indicate like parts in the several views, and

30 Figure 1 is a top plan view of the switch with the cover plate in position.

Figure 2 is a similar view with the top removed.

35 Figure 3 is a vertical longitudinal section through the switch and its casing.

Figure 4 is a vertical transverse section looking toward the pole changing end of the switch.

40 Figure 5 is a bottom plan view of the switch.

In the present embodiment there is shown a switch having a casing provided with a bottom 10, side walls 11 and end walls 12.

45 This casing also has a top 13 removably secured by suitable means to the body of the casing.

Within the casing centrally thereof is a supporting block 14 of insulating material 50 and this block is pivoted centrally of its sides on the pivot screws 15 which extend through the side walls 11. On each side edge of the tilting block 14 is fixed a contact blade 16 which projects at both ends 55 beyond the block 14. One end of each of these blades slidingly engages a respective

contact rod 17 extending vertically of the casing adjacent one end wall, each rod being secured at both ends to the casing and having its lower end connected to a binding 60 post 18 mounted on the under side of the bottom 10.

Within the opposite end of the casing is a pair of upper fixed contacts 19 and a pair of lower fixed contacts 20, the pairs of contacts being positioned for selective engagement by the blades as the latter are tilted up or down at this end of the switch. Moreover, when the blades are disposed centrally of their tilting movement they will be out 70 of contact with both pairs of fixed contacts. These two pairs of fixed contacts are cross connected by wires 21 running down through one end wall and crossing each other on the bottom 10, and these wires terminate in binding posts 22 by which the switch may be 75 connected to wires leading to one or more lamps or other translating device such as reversing motor. Thus, when this end of the block is pushed down the connections are 80 made so that one post 22 forms the positive connection and the other the negative while, when the block is tilted in the opposite direction the polarity of these terminals is reversed. An important feature of the invention resides in the provision of the single contact rod 17 with which the contact blade 16 is constantly engaged, the other end of the contact 16 selectively engaging the fixed contacts 20. It is now possible to eliminate 90 one of the lead wires and binding post that would ordinarily be connected to double spaced contacts, and with the single continuous contact rod, the same objects are accomplished with a less number of elements. 95

Carried by the block 14 is a pair of spaced push buttons 23, there being one on each side of the pivotal axis, and these push buttons protrude through suitable openings in the top 13. 100

It will be plain that by pushing either button down to the extent of its full movement the switch will be closed but that with both buttons on a level the switch will be open. Moreover, if the switch is connected to a reversing motor pushing one button will cause the motor to run in one direction and pushing the other button will cause the motor to run in the reverse direction. 105

It is to be noted that the switch thus constructed is entirely free from springs or other parts liable to get out of order. 110

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a switch of the kind described, a casing, an insulating block pivoted centrally of its length within said casing for tilting movement, a pair of knife switch blades each mounted on a respective side of the tilting block and projecting at both ends beyond the block, a pair of fixed contact rods at one end of the casing and positioned to be slightly engaged by the portions of the blades projecting from one end of the block throughout their full range of movement, a pair of upper fixed contacts and a second pair of lower fixed contacts in the paths of the remaining ends of said blades, terminal connecting posts for said fixed contacts, a single connecting post for each contact rod leading to a source of energy, and means to actuate the switch.

2. In a switch of the kind described, a casing, an insulating block pivoted centrally of its length within said casing for tilting movement, a pair of knife switch blades each mounted on a respective side of the tilting block and projecting at both ends beyond the block, a pair of fixed contact rods at one end of the casing and positioned to be slidably engaged by the portions of the blades projecting from one end of the block throughout their full range of movement, a pair of upper fixed contacts and a second pair of lower fixed contacts in the paths of the remaining ends of said blades, terminal connecting posts for said fixed contacts, a single connecting post for each contact rod leading to a source of energy, and a pair of push buttons fixed to the tilting

block on opposite sides of its pivotal center and projecting through the top of said casing.

3. In a switch of the kind described, a casing, an insulating block pivoted centrally of its length within said casing for tilting movement, a pair of knife switch blades each mounted on a respective side of the tilting block and projecting at both ends beyond the block, a pair of fixed contact rods at one end of the casing and positioned to be slidably engaged by the portions of the blades projecting from one end of the block throughout their full range of movement, a pair of upper fixed contacts and a second pair of lower fixed contacts in the paths of the remaining ends of said blades, terminal connecting posts for said fixed contacts, a single connecting post for each contact rod leading to a source of energy, means to actuate the switch, and wires connecting the contacts of one of said pairs with the contacts of the other pair in crossed relation.

4. In a switch of the kind described, a casing, an insulating block pivoted centrally of its length within said casing for tilting movement, a pair of knife switch blades each mounted on a respective side of the tilting block and projecting at both ends beyond the block, a pair of fixed contact rods at one end of the casing and positioned to be slidably engaged by the portions of the blades projecting from one end of the block throughout their full range of movement, a pair of upper fixed contacts and a second pair of lower fixed contacts in the paths of the remaining ends of said blades, terminal connecting posts for said fixed contacts, a single connecting post for each contact rod leading to a source of energy, a pair of push buttons fixed to the tilting block on opposite sides of its pivotal center and projecting through the top of said casing, and wires connecting the contacts of one of said pairs with the contacts of the other pair in crossed relation.

In testimony whereof I affix my signature.
JOHN DOMINICZAK.
